UNITED STATES PATENT OFFICE.

JAMES DETERMAN, OF NEW YORK, N. Y.

TIE-HOLDER FOR SHOES.

No. 819,413.

Specification of Letters Patent.

Patented May 1, 1906.

Application filed April 25, 1904. Serial No. 204,710.

To all whom it may concern:

Be it known that I, JAMES DETERMAN, a citizen of the United States, residing at the city of New York, borough of Brooklyn, 5 Kings county, in the State of New York, have invented certain new and useful Improvements in Tie-Holders for Shoes, of which the following is a full, clear, and exact specification.

10 My invention relates to improvements in means for securing the ends or bows of shoe-laces; and the same has for its object more particularly to provide a neat, simple, and efficient device which may be easily applied 15 to a shoe without marring its appearance or interfering in any way with the shoe-lace and the usual method of tying the same.

To these ends my invention consists in the novel details of construction and in the combination, connection, and arrangement of parts hereinafter described and then pointed out in the claims.

In the accompanying drawings, forming part of this specification, wherein like letters 25 of reference indicate like parts, Figure 1 is a perspective view of a shoe with a holder applied thereto made according to and embodying my invention. Fig. 2 is a section on the line 2 2 of Fig. 1, showing the holder 30 and adjoining parts on an enlarged scale. Fig. 3 is a top or face view, on an enlarged scale, showing the holder before attachment to a shoe. Fig. 4 is a section thereof, taken on the line 4 4 of said Fig. 3; and Fig. 5 is a 35 detail sectional view illustrating a modified form of post construction.

In said drawings, 10 designates a shoe of ordinary construction, which is provided with the usual lacing 11. Arranged upon one side 40 of the shoe-upper adjacent to its edge is secured a hollow stud or post 12, which is struck up from a triangular base 13, the corners of which are bent to form prongs and are adapted to be forced through the leather 45 of the upper, whereby to secure said stud or post 12 in position thereon.

14 denotes a transverse slit arranged in said stud or post 12, terminating at its inner end just above the base 13 in semicircular recesses 15, and 16 16 denote apertures arranged eccentrically in the sides of the stud or post 12 adjacent to the outer end of the slit 14.

17 denotes a bail elliptical in outline and 55 curved, as shown at Figs. 2 and 4.

The end portions 18 of said bail 17 are ar-

ranged substantially parallel with the longitudinal axis of said bail 17, while the extremities 19 of said end portions 18 are arranged at right angles thereto and extend 60 through the apertures 16 in said stud or post 12.

The bail 17 being curved, as shown at Figs. 2 and 4, to conform to the shape of the foot at the instep and the stud or post 12 so situated relatively to the knot of the lacing-bow, the said bail 17 when adjusted to the position illustrated at Figs. 1 and 2 will inclose the knot of the bow and bear upon the portions of the loops and ends of the bow and hold the 70 same under spring-pressure firmly against the surface of the upper beneath the same, owing to the ends of the bail 17 being engaged and held within the recesses 15 15 in the stud or post 12 at the inner edge of the 75 slit 14.

In the modification illustrated at Fig. 5 the post 20, carrying the bail 21, is shown provided with an annular flange 22 and below said flange with an eyelet portion 23, 80 whereby said post may be secured to the leather or fabric 24 of a shoe.

It is to be noted that in carrying out my invention the application of the holder to the shoe in no way interferes with the tying of 85 the lace in the ordinary manner or mars the appearance of the shoe or interferes in any way with the comfort of the wearer.

Without limiting myself to the details of construction, which may be varied within the 90 scope of the invention, what I claim, and desire to secure by Letters Patent, is—

1. A tie-holder for shoes comprising a post, means for securing the same to a shoe, said post having a transverse slit therein terminating in recesses at one side of said post, apertures in said post to the rear of said recesses, and a bail consisting of a body portion having lateral members extending outwardly therefrom, adapted to be maintained under 100 spring-pressure in said slit and recesses, and the ends of said lateral members in the apertures aforesaid, substantially as specified.

2. A tie-holder for shoes comprising a post, means for securing said post to a shoe, said 105 post having a slit extending through the same provided with recesses at one end thereof, and apertures in the sides of said post adjacent to the opposite end of said slit, and a bail comprising an elliptical body portion having substantially parallel projections extending therefrom terminating in ends bent 110

at right angles thereto and extending through the apertures in said post, said parallel projections being adapted to work in the slit of the post and their ends to be engaged by the recesses at one end thereof, substantially as specified.

3. A tie-holder for shoes, comprising a post, said post having a base having a plurality of corners adapted to be passed through its support and bent inwardly thereunder, and a slit extending through said post having recesses at one end thereof, said post having also apertures in its sides adjacent to the opposite end of said slit, and a bail comprising an elliptical body portion having substantially

parallel projections extending therefrom terminating in ends bent at right angles thereto and extending through the apertures in said post, said parallel projections being adapted to work in the slit of the head and their ends engaged by the recesses adjacent to one end thereof, substantially as specified. 20

Signed at the city of New York, in the county and State of New York, this 20th day of April, 1904.

JAMES DETERMAN.
